(57) **CLAIM**

The ornamental design for a combined dual digital display for autonomous vehicles and robotic drones, as shown and described.

DESCRIPTION

FIG. 1 is an isometric view of a combined dual digital display for autonomous vehicles and robotic drones showing my new design in an environment of use;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof; and,

FIG. 8 is an isometric view of the combined dual digital display for autonomous vehicles and robotic drones in an open configuration shown in an environment of use.

The broken lines show environment that form no part of the claimed design.
